UNITED STATES PATENT OFFICE.

JOSEPH H. GOULDSBERRY, OF TEUTONIA, WEST VIRGINIA.

CYLINDER-BORING MACHINE.

No. 810,114.

Specification of Letters Patent.

Patented Jan. 16, 1906.

Application filed February 15, 1905. Serial No. 245,741.

To all whom it may concern:

Be it known that I, JOSEPH H. GOULDSBERRY, a citizen of the United States, residing at Teutonia, in the county of Marshall 5 and State of West Virginia, have invented certain new and useful Improvements in Cylinder-Boring Machines, of which the following is a specification.

The primary intention of this invention is 10 the provision of a mechanism designed most especially for boring or truing engine-cylinders, although it may be used with equal advantage for boring ordnance and articles of kindred nature usually requiring heavy and 15 specially-constructed lathes.

The present invention relates more particularly to the mountings, whereby the mechanism may be attached to the cylinder or article to be bored, to the drive mechanism for 20 operating the boring-tool, and to the feed mechanism, whereby the boring-tool is advanced in the operation of the machine.

For a full description of the invention and the merits thereof and also to acquire a 25 knowledge of the details of construction of the means for effecting the result reference is to be had to the following description and accompanying drawings.

While the invention may be adapted to 30 different forms and conditions by changes in the structure and minor details without departing from the spirit or essential features thereof, still the preferred embodiment thereof is shown in the accompanying drawings, in 35 which—

Figure 1 is a top plan view of a boring mechanism embodying the invention, the cylinder being in section. Fig. 2 is a section on the line $x-x$ of Fig. 1 looking in the direction 40 of the arrows, showing the band pulley and crank in full. Fig. 3 is a section on the line $x-x$ of Fig. 1 looking in the opposite direction, the full lines showing the feed-trains in gear and the dotted lines showing said feed-trains 45 out of gear. Fig. 4 is a transverse section on the line $y-y$ of Fig. 1 looking in the direction of the arrows, the dotted lines showing a hinged section moved so as to release the feed-screw coöperating therewith. Fig. 5 is 50 a sectional view of the cutter-head and adjunctive parts on a larger scale. Fig. 6 is a detail view of a spider for supporting the outer end of the boring-bar when the cylinder is disconnected from its bed or supporting-framework.

Corresponding and like parts are referred

to in the following description and indicated in all the views of the drawings by the same reference characters.

The cylinder or like part to be bored or 60 trued is represented at 1, and 2 indicates the supporting bed or framework therefor. Usually an end of the boring-bar 3 is supported in the gland 4 of the stuffing-box located upon the part forming the closure for the end of 65 the cylinder connected to the bed or framework 2. When the cylinder or like part is disconnected from its framework and is open at both ends, a spider 5, such as shown in Fig. 6, is employed for supporting the end of the 70 boring-bar 3 opposite to that acted upon by the feed and drive mechanisms. The spider 5 is similar in connection to the spider 6, as shown in Fig. 1, and is provided with set-screws 7^a, threaded in offstanding parts of the 75 arms and adapted to center the spider and connect it to the end of the cylinder or like part 1, as will be readily comprehended.

The operating mechanism is applied to a 80 suitable framework which is attached in any convenient and suitable manner to the spider 6 and which, as shown, comprises similar members 7, having a parallel disposition and spaced apart a distance to receive the working elements. The boring bar 3 passes 85 loosely through the spider 6, members 7, and intermediate connection 8 and has a feather-and-spline connection with a spur-gear 9, mounted in any suitable way in the members 7 and formed with or having connected there- 90 to a pinion 10 for rotation therewith. Standards 11 are projected from the end portions of the member 7 adjacent to the spider and are provided at their upper ends with bearings in which a transverse shaft 12 is mount- 95 ed, said shaft being adapted to be driven by any suitable source of power and, as shown, is provided at one end with a crank 13 and at the opposite end with a band-pulley 14. A worm-gear 15, fast upon the shaft 12, is in 100 mesh with the spur-gear 9, so as to impart motion thereto when the shaft 12 is in operation.

A cross-head 16 is connected to the outer 105 end of the boring-bar, which latter is journaled therein, said cross-head being confined between a set-collar 17, secured to a reduced part of the boring-bar and the shoulder formed at the base of said reduced part. Guide-rods 18 project from the framework 7, 110 passing loosely through openings in the end portion of the cross-head, and give proper di-

rection thereto. Feed-nuts 19, provided at opposite ends of the cross-head, coöperate with feed-screws 20 to advance the cutting or boring tool to its work. The feed-screws 20 are mounted at their inner ends in a member 7 of the framework and are provided with gear-wheels 21, fast thereto and constituting elements of gear-trains. The feed-nuts 19 are composed of sections, one section being fast with the cross-head and the opposite section fast with a pivoted part 22, hingedly or loosely connected at one end to the cross-head and provided at the opposite end with a suitable clamp or fastening 23. When the pivoted sections 22 are released and thrown out of the way, the cross-head 16 may be moved quickly in or out, thereby providing for rapid adjustment of the boring-bar and cutting-tool carried thereby. When the sections 22 are closed upon the cross-head and secured by the fastenings 23 and the feed-screws 20 are set in motion, the boring-bar is slowly moved in the direction of its length, so as to properly advance the cutting-tool to its work.

25 A gear-train 24 coöperates with each feed-screw and is carried by a suitable frame 25, mounted to turn upon the respective feed-screw or in line therewith, so as to remain in mesh at all times with the coöperating gear-wheel 21. The swinging end of the pivoted frame 25 is curved, as shown at 26, and provided with a slot 27, which receives a fastening 28, by means of which the swinging end 30 of said pivoted frame is held to the framework 7 in the desired position. The gear-wheel 29, remote from the gear-wheel 21, is adapted to be thrown into and out of engagement with the pinion or gear element 10, as shown most clearly by the full and dotted lines in Fig. 3. When the gear elements 29 and 10 are in meshing relation and the shaft 12 is rotated, the boring-bar 3 receives a simultaneous rotary and longitudinal movement, whereby the boring or cutting tool is operated and advanced to its work.

35 The boring or cutting tool comprises a head 30, which is adapted to be secured to the boring-bar 3 by means of a set-screw 31. A bit 32 is adjustably connected with the head 30 by means of a bolt or suitable fastening 33 and is adjustable by means of a set-screw 34, threaded into the head 30 and adapted to engage at its outer end with a shoulder or stop 35 near the outer end of the bit. The provision of the set-screw 34 enables adjustment of the bit to a nicety and in a positive manner.

40 When it is required either to bore or true a cylinder, the boring-bar 3 is mounted in the gland at one end of said cylinder and the spider 6 is fitted to the opposite end of said cylinder in the manner set forth. Upon rotating the shaft 12, either by hand or power, the 45 boring-bar receives a rotary movement and

is simultaneously moved inward by the action of the feed-screws 20, thereby advancing the boring or cutting tool simultaneously with its rotation. Obviously the mechanism is well adapted for boring ordnance or 70 similar articles generally requiring heavy lathes and special machinery. When not required for immediate use, the mechanism may be laid aside, so as not to occupy valuable space or be in the way. 75

Having thus described the invention, what is claimed as new is—

1. In combination, a boring-bar, a head adjustable thereon and provided in one side with a recess and in an edge with a threaded opening, means for securing the head to the boring-bar in an adjusted position, a bit seated in the recess of said head and adjustable therein and provided with an offset or shoulder, a set-screw threaded into the opening extended inward from the edge of the head and adapted to engage with said offset of the bit, and means for securing the bit to the head in an adjusted position. 85

2. In a tool of the character described, the combination of a framework, guide-rods supported thereby and extended therefrom, feed-screws mounted in said framework, a cross-head slidable upon said guide-rods and comprising movable portions between which 95 said guide-rods and feed-screws are received, feed-nuts coöperating with the feed-screws and confined between the parts of the cross-head, fastening means for securing the parts of the cross-head when closed upon the guide-rods and feed-nuts, a bar rotatably mounted in the framework and cross-head and movable with the latter and slidable in said framework and provided with cutting mechanism, and operating-gearing between said rotatable 105 bar and feed-screws and supported by the said framework.

3. In a machine of the character set forth, a framework comprising spaced members, guide-rods connecting said members and extended therefrom, feed-screws mounted in the framework, a cross-head slidable upon said guide-rods, a bar provided with cutting mechanism and mounted in said cross-head to move therewith and having both rotary 115 and sliding movement in the framework, a driver mounted upon said bar and having a sliding-key connection therewith, pivoted frames mounted coaxially with the feed-screws, and a train of gearing mounted upon 120 each of the pivoted frames and having connection with the respective feed-screws and adapted to be thrown into and out of gear with the aforesaid driver, the pivoted frames, trains of gearing and driver being arranged 125 between the spaced members of the aforementioned framework.

4. A machine of the character described comprising a spider, clamp-screws fitted in the arms of said spider, a framework com- 130

prising spaced members, connecting means between said framework and spider, guide-rods connecting the spaced members of the framework and extended therefrom, feed-screws mounted in the framework, a cross-head having movable parts between which are received said guide-rods and feed-screws, feed-nuts confined between the movable parts of the cross-head and receiving the feed-screws, fastening means for securing the movable parts of the cross-head when closed upon the guide-rods and feed-nuts, a boring-bar provided with cutting mechanism mounted in the cross-head and framework and having both rotary and sliding movement with reference to said framework and movable with the cross-head, a driver mounted upon the

boring-bar to turn therewith but admitting of said bar having sliding movement therethrough, frames pivoted coaxially with the feed-screws, and trains of gearing supported by said pivoted frames and connected with the respective feed-screws and adapted to be thrown into and out of gear with the said driver, the pivoted frames, trains of gearing and driver being arranged between the spaced members of said framework. 20 25

In testimony whereof I affix my signature in presence of two witnesses.
